LIQUID COOLING DEVICE

John S. MacArthur, Attica, N. Y.

Application August 16, 1933, Serial No. 685,433

5 Claims. (Cl. 62—91.5)

My present invention has reference to a liquid cooling device, and has for its primary object the provision of a device in which liquid will be cooled and retained in a cooled condition for an 5 extended length of time.

A further object is the provision of a liquid containing and dispensing device in which dry ice is employed as the refrigerant and which includes means for preserving the dry ice for a 10 greater length of time than is ordinary, sustaining the ice in a chamber that is divided from the liquid containing compartment, providing means for hermetically sealing both of the compartments, and also provided with means for directing 15 the gases from the refrigerant chamber into and around the liquid containing compartment and likewise means for permitting such gases to escape to the atmosphere.

The invention will be fully and comprehensively understood from a consideration of the following detailed description when read in connection with the accompanying drawings which form part of the application, with the understanding, however, that the improvement is capable of 25 extended application and is not confined to the exact showing of the drawings nor to the precise construction described and, therefore, such changes and modifications may be made therefrom as do not affect the spirit of the invention 30 nor exceed the scope thereof as expressed in the appended claims.

In the drawings:

Figure 1 is an approximately central longitudinal sectional view through the improvement.

Figure 2 is a sectional view approximately on the line 2—2 of Figure 1.

Figure 3 is a perspective view of one of the latches.

Figure 4 is a greatly enlarged sectional view 40 approximately on the line 4—4 of Figure 1.

Figure 5 is a sectional view approximately on the line 5—5 of Figure 4.

Figure 6 is a detail elevation to more fully illustrate the means for latching the cover on the 45 device.

The body 1 of the improvement is preferably in the nature of a cylinder having a closed bottom and an open top. The body 1 is preferably of sheet steel whose seams are welded and both the 50 inner and outer surfaces of the body are baked with white enamel. This is especially true with respect to the inner surface as the body 1 provides the liquid container and the enamel renders the same sanitary. Both of the enamel faces 55 assist in rendering the container impervious and free from atmospheric influence. The container 1 has one of its sides, at its bottom provided with an outlet opening to which is attached a faucet 2. The faucet is preferably of the pressure type and

the spring influenced valve therein is, of course, normally seated.

In the bottom of the body or container 1 there is arranged a wire and spider-like support 3 whose upper and central portion is of cup-shaped 65 formation and is indicated for distinction by the numeral 4. The open or skeleton rack or support 3 is of aluminum alloy wire, and the upper concave or cup-like portion thereof receives therein the bottom of the cylindrical body 5 that 70 provides the refrigerant chamber. The chamber 5 also has its top open, and the rack or support 3 spaces the chamber from the container 1, arranging the said chamber in the center of the container.

The chamber 5 is of aluminum and has arranged therein and spaced from the side and top walls thereof a reticulated basket 6 which is also of aluminum.

Resting on the bottom of the basket 6 and 80 holding the said basket on the bottom of the chamber 5 there is a disc 7. The disc is of a soft hydrous body, such as soapstone or talc.

The closure for the body is indicated by the numeral 8 and has an outstanding peripheral 85 grooved bead 9 in which is seated a ring gasket 10. The closure for the cylindrical refrigerant chamber 5 is indicated by the numeral 11 and is also provided with a peripheral outstanding grooved bead 12 in which is received a compressible ring gasket 13. The disc closure 11 is secured to the disc closure 8 by double headed rivets 14, there being arranged around the rivets and in contact with the confronting faces of the closures 8 and 11 spacer sleeves 15. To two of the 95 rivets 14 on the ends thereof that extend through the closure 9, there is secured an arched handle 16. The closure 8, at spaced intervals, has its beaded edge provided with cam ribs 17 and there is pivotally secured on the sides of the container 1 the lower ends of latch plates 18. Each latch 100 plate has its upper end formed with a lateral extension 19 whose outer edge is flanged downwardly, as at 20, and on each extension 18 there is a finger piece 21, whereby the latches may have their ends 19 swung over the cam ribs 17 for securing the closures 11 and 8 on the chamber 5 and body or container 1 and to establish a hermetically sealed joint between the said closures, chamber and body. The downturned flanges 20 contact with the inner faces of the cam ribs 17, as disclosed by Figure 1 of the drawings.

The closure 11, at the center thereof, is provided with a round opening surrounded by a flange 22 whose outer end is in contact with the inner face of the closure 8 and may be welded thereto. The flange 22 is provided with a lateral port 23. The closure 8 is also provided with a central opening surrounded by an outwardly extending and exteriorly threaded flange 24 whose

bore alines with that of the flange 22. Arranged for turning in the cylindrical flanges 22 and 24 there is a short tube 25 that has a port 26 to aline with the port 23. Centrally fixed on the outer 5 end of the tube 25 there is a plate 27 formed with laterally extending shoulders 28 that rest on the outer end of the flange 24. The outer edge of the plate 27 is arched, as at 29, and is disposed opposite the inner arched portion 30 of a cap- 10 member 31. The arched or dome-shaped portion 30 of the cap member is provided with restricted apertures 32 disposed directly opposite the arched edge of the plate 27. The cap member has an outwardly extending portion 33 which is periph- 15 erally milled and provides a hand grip or wheel and from this portion 32 the cap has an interiorly threaded extension 34 that is interiorly threaded to engage with the threads on the flange 24. The elements just described provide the vent 20 for the device. By screwing the cap until the same contacts with the periphery of the plate 27 the vent opening 32 will be closed, but there will be a frictional engagement between the dome-shaped top of the cap and the plate 27 25 sufficient to turn the tube 25 to bring its port 26 into or out of alignment with the port or aperture 23. It is to be understood that a quantity of dry ice is arranged in the chamber 5, and rests on the soap stone disc 7 and is prevented 30 from contact with the chamber by the reticulated basket 6. The gases from the ice will be directed through the registering ports or apertures 26 and 23 and will be caused to circulate around the interior of the container 1 and the liquid therein. 35 The liquid, of course, is poured into the container before the closures are applied. The closure 11 for the chamber 5 is of aluminum but the closure 8 for the container 1 is preferably of steel and has enamel paint on both of its faces. 40 The hermetically sealed device will preserve the dry ice for a greater period of time than can the same be preserved by any other means known to me. By turning the cap in a second direction the same will be brought away from the plate 27 so that the gases generated by the dry ice 45 in the chamber 5 can escape through the restricted port or aperture 31 to the atmosphere.

Gases generated by the dry ice will first collect between the reticulated basket 6 and the inner face of the cylindrical chamber 5 so that the same will slowly circulate therefrom around the interior of the container 1, which, of course, adds to the cooling effect of the liquid in the container. As is well known dry ice evaporates very 55 quickly and by placing the soapstone disc 7 in the bottom of the chamber 5 or rather in the bottom of the basket 6, and upon which soapstone the dry ice rests the said disc 7 will absorb and consequently accumulate the cold that is 60 passed off of the dry ice which also assists in preserving the ice and likewise the said disc in throwing off its accumulation will assist in cooling and retaining the liquid in the container 1 in a cool condition for a greater length of time than could otherwise be accomplished by the 65 employment of dry ice as a refrigerant. With my improvement the liquid is cooled in a quicker manner and at a lower degree of temperature, without freezing than can be accomplished by 70 any other device or method with which I am acquainted, and it is believed that the foregoing

description when read in connection with the accompanying drawings will fully and clearly set forth my improvement, its construction and advantages so that further detailed description will not be required.

Having described the invention, I claim:

1. A liquid cooling device comprising a hollow body having an open top, a container for dry ice arranged in the body and also having an open top, a disc of soft hydrous material in the container on which the dry ice rests, connected closures for the container and body, swingable latches on the body, cam ribs on the closure for the body to be engaged by the latches, for hermetically sealing the body and the container and valve means operable from the exterior of the body for directing gases from the container into and around the body, and for likewise directing such gases to the atmosphere.

2. A liquid cooling device comprising a hollow body having an open top and a faucet in the bottom, a spider in the bottom of the body, a container providing a chamber for a dry ice refrigerant resting on the spider, a reticulated basket in the container spaced from the side walls thereof, a soft hydrous body in the basket holding the bottom thereof against the bottom of the chamber and affording a rest for the dry ice, connected closures for the open top of the body and for the chamber and having open beaded edges and gaskets in said beads, pivotally supported latch members in the body having U-shaped ends provided with finger holds, and the closure for the body having cams thereon to be engaged by the U-shaped ends of the latches for hermetically sealing the body and the chamber, and valve controlled means operable from the exterior of the closure for the body and communicating with the chamber for directing gases from the chamber into and around the body or for directing such gases to the atmosphere.

3. A liquid cooling device comprising a hollow body, a container for dry ice in the body, means for supporting the container from contact with the body, connected, top closures for the container and body and the closure for the container being provided with a port, a valve mounted in the closures having a port adapted to register with the port of the closure of the container for directing gases from the container within the body.

4. A liquid cooling device comprising a hollow body, a container for dry ice in the body, connected top closures for the container and body, means supporting the container from contact with the body, a valve mounted in an opening of the connected closures for directing gases from the container within the body, and means associated with the closure for the body for operating the valve.

5. A liquid cooling device comprising a hollow body, a container for dry ice in the body, connected top closures for the container and body, means supporting the containers from contact with the body, a valve mounted in registering openings of the connected closures for directing gases from the container within the body, a cap for closing the openings of the closures, and means interposed between said cap and valve for permitting of a manual operation of said valve.

JOHN S. MACARTHUR.
